Patented July 13, 1915.

UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

FIREARM.

1,146,503.

Specification of Letters Patent. Patented July 13, 1915.

Application filed May 3, 1915. Serial No. 25,490.

To all whom it may concern:

Be it known that I, THOMAS C. JOHNSON, a citizen of the United States, residing at New Haven, in the county of New Haven 5 and State of Connecticut, have invented a new and useful Improvement in Firearms; and I do hereby declare the following, when taken in connection with the accompanying drawings and the characters of reference 10 marked thereon, to be a full, clear, and exact description of the same, and which said drawings constitute part of this application, and represent, in—

Figure 1, a broken view in side elevation 15 of a firearm constructed in accordance with my invention. Fig. 2, a broken detached view in side elevation of the front end of the receiver, showing its provision with a depending abutment-lug. Fig. 3, a view 20 thereof in broken transverse section on the line *a*—*b* and looking forward toward the rear face of its abutment-lug. Fig. 4, a detached view of the receiver in front elevation. Fig. 5, a detached view in rear elevation 25 of the forearm. Fig. 6, a detached view in front elevation of the butt-stock.

My invention relates to an improvement in that class of firearms in which the stock is divided into two parts known as the forearm 30 and the butt-stock, the object being to provide improved means for supporting the adjacent ends of the forearm and butt-stock and for fastening the front end of the guard of the firearm.

With these ends in view, my invention consists in a receiver having its forward end provided with a depending abutment-lug adapted to support the adjacent ends of the forearm and butt-stock and constructed 40 with a rearwardly extending finger for the attachment of the guard.

My invention further consists in certain details of construction and combination of parts as will be hereinafter described and 45 pointed out in the claims.

In carrying out my invention as herein shown, I form a rearwardly extending horizontal finger 2 upon the rear face of an

abutment-lug 3 depending from, and preferably formed integral with, the forward 50 end of the receiver 4 which in other respects may be of any approved construction, according to the character of the gun. The said finger 2 is counter-bored and threaded as at 5 for the reception of a screw 6 passing 55 upward through the extreme front end of the guard 7 which may be of any approved construction. The extreme forward end of the guard 7 abuts directly against the portion 8 of the flat rear face 9 of the lug 3, 60 while the upper face of the forward end of the guard is brought to a bearing by the screw 6 against the lower face of the finger 2 which enters a cut or recess 10 formed for its reception in the flat front face of the 65 butt-stock 11 which is supported, as shown, by the entrance of tenons 12 formed upon its forward end into narrow cuts or sockets 13 in the flat rear face 9 of the abutment-lug 3 and also by the finger 2. As shown, the 70 front face of the lug 3 is formed with a large shallow recess 18 having a flat bottom 14 and receiving a tenon 15 of corresponding shape formed upon the rear end of the forearm 16 which is permanently attached to the 75 barrel 17 in any of the well known ways. The said barrel 17 is screwed in the usual way into the receiver 4 and in case it comes loose from any cause is prevented from turning by the tenon 15 acting as a dowel by its entrance into the recess 18. In its external contour, the lug 3 conforms to the curvature 80 of the adjacent ends of the butt-stock 11 and forearm 16 so as to form a bridge between the two and a virtual extension of both. 85

The particular manner of adapting the front and rear faces of the lug 3 to receive the adjacent ends of the butt-stock and forearm may be varied, my present invention relating in particular to the provision of the 90 said lug 3 with a rearward projection 2 for the attachment of the forward end of the guard.

I claim:

1. A receiver for small arms provided at 95 its forward end with a depending abutment-

lug adapted to support the adjacent ends of a forearm and butt-stock and provided with a rearwardly extending finger for the attachment of the forward end of the guard of the arm.

2. A receiver for small arms provided at its forward end with a depending abutment-lug adapted to support the adjacent ends of a forearm and butt-stock and provided with

a rearwardly extending finger for supporting the forward end of the butt-stock.

In testimony whereof, I have signed this specification in the presence of two subscribing witnesses.

THOMAS C. JOHNSON.

Witnesses:

FREDERIC C. EARLE,
FRANK A. PAUL.
